LIFT DOOR

Thorvald Madland, Chicago, Ill., assignor, by
mesne assignments, to The Youngstown Steel
Door Company, Cleveland, Ohio, a corporation
of Ohio

Application August 3, 1934, Serial No. 738,231

11 Claims. (Cl. 20—22)

This invention relates to lift doors.

It is among the objects of this invention to provide a lift door embodying a relatively longitudinally movable carriage including rolling means and wherein the amount of friction between the parts shall be materially reduced; to provide a more stable lift structure utilizing relatively longitudinally movable door supporting means; and to provide a lift structure of sturdier construction and of reduced weight.

With these and other objects in view, which will become clear as the description of the invention proceeds, this invention comprises the novel structure and combination of parts hereinafter described and more particularly pointed out and defined in the appended claims.

In the drawings forming part of this specification:

Figure 1 is a partial elevation of a railway freight car upon which a door embodying the instant invention is mounted, the door being shown in lowered position;

Figure 2 is a view similar to Figure 1, the door being illustrated in elevated position;

Figure 3 is a vertical section taken on line 3—3 of Figure 1;

Figure 4 is a vertical section taken on line 4—4 of Figure 1;

Figure 5 is a vertical section taken on line 5—5 of Figure 1;

Figure 6 is a vertical section taken on line 6—6 of Figure 7, showing a modified form of the invention;

Figure 7 is a view similar to Figure 1 showing in elevation the modified form of invention illustrated in Figure 6;

Figure 8 is a horizontal section taken on line 8—8 of Figure 1; and

Figure 9 is a vertical section taken on line 9—9 of Figure 7.

Referring to the drawings and more particularly to the embodiment of the invention illustrated in Figures 1 to 5, inclusive, and Figure 8, the numeral 10 designates a portion of the siding 45 of a railway freight car upon which a sliding door 11 is mounted. The door 11 is of a well-known metallic construction and is merely illustrative of one type of door with which the invention may be employed. The side door comprises 50 a metallic panel 12 provided with spaced horizontal corrugations 13 and vertical corrugations 14 and 15 with which the horizontal corrugations merge. The door is of the sliding type and is supported for such movement upon a track 16 supported from a side sill 17 by means of a plu-

rality of brackets, one of which is indicated at 18. Rivets are utilized to secure the track and track brackets to the side sill. The structure of the lower portion of the door comprises a substantially tubular formation 19 secured to the lower 5 horizontal margin of the panel 12 by means of a plurality of rivets 20.

The tubular formation comprises a plurality of plates 21 and 22. The plate 21 is offset to provide a horizontal flange 23 from which said plate 10 extends vertically downwardly to provide a flange 24. The plate 22 comprises a vertical flange 25 which, adjacent the lower portion thereof, is offset outwardly to provide a substantially horizontal flange 26 which, in turn, is bent downwardly to 15 provide a vertical flange 27. The upper portions of the plates 21 and 22 are secured together by the rivets 20 which fasten said plates to the lower margin of the panel 12 while the lower portions of the plates are fastened together by means of 20 rivets 28 which extend through the vertical flanges 24 and 27, respectively of the plates. By means of this construction it is to be observed that a tubular formation results, defined by the horizontal flanges 23 and 26 and the vertical 25 flanges 24 and 25.

Within the above described tubular formation is disposed a carriage 29. This carriage comprises preferably an angle member 30 arranged with one leg 31 positioned in a vertical plane 30 and the other leg 32 directed inwardly relative to the car. A roller carrying member 33 is secured to each end of the angle member 30. Each of the roller carrying members preferably comprises a pair of plates 34 and 35. The plate 35 35 is substantially straight and is disposed upon the outside of the vertical leg 31 of the angle member 30. The plate 35 has a portion 36 abutting the vertical leg 31 upon the inside thereof, said portion 36 and the plate 33 being riveted to the adjacent end of the angle member 30. From its point of securement to the angle member the plate 35 is offset inwardly as indicated at 37 to provide a portion 38 disposed in spaced parallel relationship to the plate 33. A roller 39 is disposed between the spaced portions of the plates 34 and 35 said roller being mounted upon a pin 40 fastened in the plates 34 and 35. A filler block 41 is disposed between the portion 38 of the plate 35 and the plate 34 and is riveted to said plates 50 beyond the roller. The upper surface of the filler block 41 as well as the upper surface of the adjacent portions of the plates 34 and 35 are provided with a substantially V-shaped indenture 42 adapted to receive a roller bearing 43. The 55

plate 34 is extended downwardly and is provided with a hook portion 44 within which the depending flange 45 of the track 16 is received in order to prevent accidental disengagement of the door 5 from the track. It will be clear from Figure 3 of the drawings that the depending portion upon which the hook is provided lies upon the outside of the track and in order to permit this disposition of said portion the flange 27 of the plate member 22 is coped as indicated at 46 and 47. It will be observed from Figure 1 of the drawings that this coped portion is of greater extent than the length of the depending hook portion. By means of this relationship the flange 27 is utilized 10 to limit the relative longitudinal movement of the carriage with respect to the track as hereinafter more fully set forth. The foregoing description has been applied to the structure at one end of the carriage 29 inasmuch as the construction of 15 the opposite end of said carriage is substantially the same.

A filler block 48 is disposed between and secured to the vertical flanges 24 and 25 of the plate members 21 and 22 as by means of rivets 49 in 20 spaced vertical alignment with each of the filler blocks 41 provided on the carriage. The lower surface of each of the filler blocks 48 is provided with a substantially inverted V shaped indenture 50. It will be clear from the foregoing that a 25 roller bearing lies within the area defined by the V shaped indenture 42 and the inverted V shaped indenture 50. The inverted V shaped indentures, when the door is in its normal or lowered position, are preferably out of contact 30 with the roller bearings.

In the normal or lowered position of the door it is disposed upon and has frictional engagement with the track. In the instant embodiment of the invention such frictional engagement 40 is provided by the contact between the horizontal flange 26 of the plate 22 and the track. While the weight of the door is thus carried directly by the track the arrangement of the rollers 39 is such as to engage the track and for this purpose the horizontal flange 26 is coped as indicated at 51.

In order to move the door upon the rollers 39 the weight of the door is first transferred from the track to the rollers. Such transference of 50 the weight of the door is obtained by imparting a longitudinal movement of the carriage 29 relative to the door and the track. For this purpose a lever 52 pivoted intermediate its ends upon a boss 53 formed on a bracket 54 secured to the door extends through an opening 55 provided in the horizontal flange 23 of the plate member 21. The lower portion of the lever 52 is provided with spaced prongs 56 and 57 which extend through corresponding openings 58 and 59 formed 55 in the horizontal leg 32 of the angle member 30. It will be apparent from a consideration of Figures 1 and 2 of the drawings that as the carriage 29 is shifted longitudinally upon the track its movement will be limited by the engagement 60 of the depending portion of the carriage with one end of the recess provided in the vertical flange 27 of the plate member 22 and the roller bearings will be engaged by opposite branches of the indentures provided in the filler blocks 41 and 48. The engagement between these parts and the continued longitudinal movement of the carriage 29 will cause the roller bearings to ride up 65 the engaged branch of the V shaped indentures provided on the carriage so as to effect elevation 70 of the door, whereupon the horizontal flange 26

of the plate member 22 will be disengaged from the track. The weight of the door has thus been shifted from the track to the rollers and the door may then readily be moved upon the rollers to the desired position. When it is desired to move the door in the opposite direction the operating lever 52 will be swung in said direction so as to impart longitudinal movement to the carriage 29. The remaining opposite branches of the indentures provided on the door and on the carriage will then engage the roller bearings 43 so as to cause said bearings to roll up the engaged branches of the carriage indentures in order to elevate the door. The door may then again be readily moved upon the rollers 39. 15

A further embodiment of the invention is illustrated in Figures 6, 7 and 9 of the drawings. In this embodiment a carriage 60 is provided which comprises an angle member 61 disposed with the legs thereof in downwardly diverging relationship, whereby such legs constitute a runway 62. Within this runway and in contact with a door supporting track 63 a plurality of balls 64 are disposed. The balls 64 are maintained in spaced relationship by means of a spacer 65 provided 25 with pairs of upstanding prongs 66 and 67, between which each ball is disposed.

A plurality of spaced saddles 68 are secured upon the angle member 61. Each of said saddles comprises a plurality of V shaped indentures 30 69 and 70 adapted to receive ball bearings 71 and 72. It will be observed that the V shaped indentures and, consequently, the ball bearings disposed therein lie upon opposite sides of the axis of the angle member 61. 35

The carriage above described is preferably disposed between a substantially Z shaped member 73 and a plate member 74. The upper portion of the plate member and one vertical flange 75 of the Z shaped member are secured as by means 40 of rivets 76 to the lower horizontal portion of the panel 12. The other vertical flange 77 of the Z shaped member 73 lies in spaced relationship to the plate member 74 so as to provide space for the reception of the carriage 60. The 45 lower margin of the vertical flange 77 may be turned inwardly as indicated at 78 so as to avoid the track when the door 11 is in lowered position.

A plurality of spaced members 79 are secured 50 to the web 80 of the Z shaped member 73 and extend between the vertical flange 77 thereof and the plate 74. Each of these members 79 is provided with a plurality of inverted V shaped indentures 81 and 82 disposed in vertical alignment with the V shaped indentures 69 and 70 provided on the saddle members 68. The indentures provided on the saddle members 68 and on the members 79 provide spaces for the reception 55 of the bearing balls 71.

Frictional engagement between the door and the track in the normal or lowered position of the door is obtained by contact between the portion 78 of the vertical flange 77 and by means of the contact between the gusset members 83 and 84 secured, respectively, to the lower corners of the door. In order to break such frictional engagement and to support the door upon the balls 64 for antifrictional movement relative longitudinal movement is imparted to the carriage 70 60. For this purpose an operating lever 85 is employed, said lever being pivoted intermediate its ends upon a boss 86 formed upon a bracket 87 secured to the door. Prongs 88 and 89 formed 75 on the lower portion of the lever straddle an

abutment 90 formed on a bracket member 91 secured to the carriage. Longitudinal movement is imparted to the carriage 60 by swinging the upper end of the lever in the direction it is desired to move the door. During such longitudinal movement of the carriage the bearing balls 71 will be engaged between opposed branches of the indentures provided on the saddle members 68 and the members 79 and said bearing balls will be caused to roll up the engaged branch of the V shaped indentures provided on the saddle members. As the bearing balls move up such branches an elevating movement will be imparted to the door so that the frictional engagement of said door with the track will be broken. The weight of the door having thus been transferred to the balls 64 the door may readily be moved in the desired direction.

In both embodiments of the invention the door will automatically seat itself in frictional engagement with the track when the operating lever is released. In the instant embodiment of the invention the plate 74 is provided with a tongue 92 preferably struck out of the plate as indicated at 93. The tongue 92 overlies the ball spacer 65 and in the lowering movement of the door said tongue engages and lies upon the spacer. By this construction the weight of the door is utilized to maintain the spacer in fixed relationship with respect to the track so as to avoid accidental shifting of the balls 64 upon the track.

It will be apparent that numerous changes and modifications in the details of the invention will be clear to those skilled in the art. It is intended, therefore, that all such modifications and changes be comprehended within this invention, which is to be limited only by the scope of the claims appended hereto.

40 I claim:

1. In a car door, a carriage capable of relative longitudinal movement with respect to said door, antifriction supporting means for said carriage, longitudinally inclined guideways provided on said carriage, longitudinally inclined guideways provided on said door and antifriction means disposed between said guideways.

2. In a car door, a carriage capable of relative longitudinal movement with respect to said door, antifriction supporting means for said carriage, substantially V shaped guideways provided on said carriage, guideways of substantially inverted V shape secured to said door in spaced vertical relationship to said carriage guideways and antifriction means disposed between said guideways.

3. In a railway car having a door opening in a side thereof, a track secured to said car adjacent said opening, a door for closing said opening, said door in its lowered position having frictional engagement with said track, a carriage, antifriction means supporting said carriage upon said track for longitudinal movement relative to said door and said track, means for imparting longitudinal movement to said carriage and means for converting said longitudinal movement of said carriage into a vertical movement of said door, said latter means comprising vertically spaced longitudinally inclined guideways provided, respectively, on said carriage and said door and antifriction means disposed between said guideways.

4. In a railway car having a door opening in a side thereof, a track secured to said car

adjacent said opening, a door for closing said opening, said door in its lowered position having frictional engagement with said track, a carriage, antifriction means supporting said carriage upon said track for longitudinal movement relative to said door and said track, means for imparting longitudinal movement to said carriage, substantially V shaped guideways provided on said carriage, substantially inverted V shaped guideways provided on said door, antifriction means disposed between said guideways whereby longitudinal movement of said carriage will effect rolling engagement between said antifriction means and oppositely inclined branches of said door and carriage guideways and elevation of said door above said track.

5. In a car door, a carriage capable of relative longitudinal movement with respect to said door, antifriction supporting means for said carriage, substantially V shaped guideways provided on said carriage, guideways of substantially inverted V shape secured to said door in spaced vertical relationship to said carriage guideways and roller bearing members disposed between said guideways.

6. In a car door, a carriage, a ball raceway provided on said carriage, balls seated in said raceway for supporting said carriage for longitudinal movement relative to said door, a plurality of spaced members secured to said carriage, said members being provided with longitudinally inclined guideways, ball bearings seated in said guideways, said door being provided with longitudinally inclined guideways disposed above said ball bearings.

7. In a car door, a carriage, a ball raceway provided on said carriage, balls seated in said raceway for supporting said carriage for longitudinal movement relative to said door, a plurality of spaced saddles secured to said carriage, guideways provided on said saddles disposed upon opposite sides of the axis of said carriage, guideways provided on said door vertically aligned with said saddle guideways, said guideways being longitudinally inclined, and ball bearings disposed between said guideways.

8. In a car door, a carriage, a ball raceway provided on said carriage, balls seated in said raceway for supporting said carriage for longitudinal movement relative to said door, a plurality of spaced saddles secured to said carriage, V shaped guideways provided on said saddles disposed upon opposite sides of the axis of said carriage, inverted V shaped guideways provided on said door vertically aligned with said saddle guideways and ball bearings disposed between said guideways.

9. In a railway car having a door opening in a side thereof, a track secured to said car adjacent said opening, a door for closing said opening, said door in its lowered position having frictional engagement with said track, a carriage, a ball raceway provided on said carriage, balls disposed upon said track and seated in said raceway for supporting said carriage for longitudinal movement relative to said door and track, a lever mounted upon said door for imparting longitudinal movement to said carriage, V shaped guideways provided on said carriage, ball bearings disposed in said raceways, inverted V shaped guideways provided on said door vertically above said carriage guideways, said door guideways being out of contact with said ball bearings when said door is in frictional engagement with said

track, said ball bearings engaging said carriage and door guideways upon longitudinal movement of said carriage to raise said door above said track.

5 10. In a railway car having a door opening in a side thereof, a track secured to said car adjacent said opening, a door for closing said opening, said door in its lowered position having frictional engagement with said track, a carriage, a ball raceway provided on said carriage, balls disposed upon said track and seated in said raceway for supporting said carriage for longitudinal movement relative to said door and track, a spacer having means disposed on opposite sides 15 of each of said balls for maintaining said balls in spaced relationship, means provided on said door for engaging said spacer in the lowered position of said door for preventing movement of said spacer, a lever mounted upon said door for imparting longitudinal movement to said carriage, V shaped guideways provided on said carriage, ball bearings disposed in said guideways, inverted V shaped guideways provided on said door vertically above said carriage guideways, said

10 15 20

door guideways being out of contact with said ball bearings when said door is in frictional engagement with said track, said ball bearings engaging said carriage and door guideways upon longitudinal movement of said carriage to raise 5 said door above said track.

11. In a railway car having a door opening in a side thereof, a track secured to said car adjacent said opening, a door for closing said opening, said door being frictionally supported in its lowered position, a longitudinally extending member, spaced rolling elements supporting said member upon said track for longitudinal movement relative to said door and track, lever means pivoted upon said door and engageable with said 15 member for imparting longitudinal movement thereto and cooperating means including rolling devices and means having inclined surfaces associated with said devices provided on said door and member for effecting elevation of said door responsive to longitudinal movement of said member and transferring the support of said door to said rolling elements.

THORVALD MADLAND.
